UNITED STATES PATENT OFFICE.

ADOLPHE EHINGER, OF NEW YORK, N. Y.

BUOYANCY-TANK.

1,081,103.

Specification of Letters Patent.

Patented Dec. 9, 1913.

Application filed March 28, 1912. Serial No. 686,789.

To all whom it may concern:

Be it known that I, ADOLPHE EHINGER, a subject of the Emperor of Germany, and a resident of the city of New York, borough 5 of Manhattan, in the county and State of New York, have invented a new and Improved Buoyancy-Tank, of which the following is a full, clear, and exact description.

10 My invention relates to buoyancy tanks such as are used in wrecking operations for the purpose of raising sunken vessels and other submerged objects.

It comprises a hollow body having means 15 for admitting air and water thereinto, and is so designed that the pressure of the water upon the outside of the same, no matter what the depth of submergence may be, is always balanced by the volume of air on the 20 inside of the tank, so that it is impossible for the tank to be crushed under any conditions that are met with in practice.

Reference is to be had to the accompanying drawings forming a part of this specification, in which the same characters of reference indicate the same parts in all the views.

Figure 1 is a perspective view, partly broken away, showing my improved tank 30 and the interior construction of the same; Fig. 2 is a vertical longitudinal sectional view showing one side of the interior of the tank; Fig. 3 is a similar view taken through the body or main portion of the 35 tank, showing the other side of the same; and Fig. 4 is a sectional view on the line 4—4 of Fig. 3, looking in the direction of the arrow.

My improved tank comprises a body 1, 40 preferably cylindrical in shape, to which are fitted conical ends 2. The ends 2 are of course soldered to the body 1, so as to make the joint connecting the ends 2 in place preferably air and water-tight; and on the 45 outside of the tank are secured rings 3, by means of metal straps 4, which are fastened in place by means of rivets 5.

6 is an ordinary drain cock, and 7 is a boss or projection placed on the bottom of 50 the body of the tank 1, opposite the drain cock 6. This boss or projection is hollow, forming a pocket or recess inside the body, and is secured to the body of the tank 1, so as to communicate with the inside of the 55 tank through an opening, and is connected to the edge of the opening by riveting or

soldering, or in any other manner that will produce an air-tight joint between the parts in question.

8 represents a pair of conduits leading 60 from opposite sides of the hollow boss 7 through the bottom of the body of the tank 1, these conduits serving to distribute fluid that enters the boss 7 to the ends of the tank, so as to enable the same to be filled 65 more rapidly than if all the fluid which enters the boss 7 had to fill the tank 1 by passing into the same through the aperture in the bottom of the tank which forms the open inner end of this boss or projection. 70

The numeral 9 represents the end of a bent pipe projecting into the boss 7 and being open at its inner end. To the end 9 is connected a section 10 which extends longitudinally of the tank and may be secured 75 to the inner surface thereof. Communicating with the opposite end of the section 10 is another section 11 which extends transversely of the tank and is substantially at right-angles to both the sections 9 and 10. 80 To the other end of the section 11 is connected a tubular section 12 which extends parallel to the section 10 and past the end of the same joined to the section 9, this section 12 in effect extending both ways past 85 the boss 7. It communicates at its opposite end with a tubular section 13 which is substantially parallel to the section 11, and to the opposite end of the connecting section 13 is secured a tubular section 14, parallel with 90 the sections 10 and 12, and of substantially the same length as the section 10; that is, the other end of the section 14 will lie in about the same transverse plane as the end 9. Joined to the tubular section 14 is a section 95 15 which extends from the boss 7 toward the drain cock 6, and communicates with a section 16, which leads outward through an aperture or port 17. The bent pipe made up of the end 9 and the sections 10 to 16 inclusive thus establishes communication between the inside of the boss 7 and tank 1, and the outside of the same, and the object of this bent pipe is to permit the tank to be filled with water when it is sunk to be 100 attached to the wreck that is to be raised.

The numeral 18 represents a conduit which leads to the side of the body of the casing 1 adjacent the drain cock 6, and the outer end of this conduit is open to receive the end of a 105 conduit 19 through which air can be pumped into the tank 1. Inside of the tank 1 the

pipe 18 is bent against the interior surface down to about the middle thereof, and then is returned on itself for a short distance, as shown at 20. At the end of the section 20 5 it is bent as shown at 21 to extend again toward the boss 7, and this section 21 is secured to the inside of the tank by means of a strap 22. At the end of the section 21 which is near 23 to the boss 7 the conduit 18 10 is bent toward its point of entry, as shown at 23, and then is again bent toward the boss 7, as shown at 24. Adjacent the edge of the boss 7 this conduit is bent longitudinally, as shown at 25, and then longitudinally, as shown at 26, 15 in the opposite direction, as shown at 26, this section 26 extending substantially along the edge of the aperture leading to the inside of the boss 7, and the length of the conduit 18 beyond the section 26 is returned 20 on itself so as to extend in the same direction as the section 25, and then is bent downward, as shown at 27, into the boss, and then upward as shown at 28, reference being had to Fig. 2. The end 28 is of course open. 25 Expressed in another way, the air supply pipe within the tank 1 is composed of two parts, the first consisting of the portions 20, 21, 23 and 24, forming oppositely-disposed connected S-shaped sections constituting 30 a compound coil extending approximately transversely to the axis of the tank, and the second part consisting of the portions 25, 26, 27 and 28, forming an S-shaped section disposed approximately parallel to 35 the axis of the tank and extending to opposite sides of the boss 7.

In practice, the tanks are utilized by having them secured in place under the water to the wrecks that are to be raised by 40 divers. When the tank is sunk it is connected up to the air pumping apparatus, but no air is pumped into the same at this time. Instead the drain cock 6 will be opened and water will flow into the interior 45 of the tank through the port 17 and pipe connected thereto and terminating in the end 9 and the boss 7, so that the interior of the tank is filled with water, any air that may be trapped therein passing out through 50 the drain cock 6, as will be readily understood. In this condition the tank can be sunk to any depth, because the internal and external pressure of the water is balanced and there is no crushing stress exerted on 55 the walls of the tank. When the diver reaches the wreck he fastens the rings 3 to the hulk thereof, preferably in horizontal position. When the raising operations are to begin the drain cocks must be shut, and 60 this is attended to by the diver after he fastens the tanks in place. Air is now pumped down through the conduit 19 and into the conduit 18, and this air will be discharged into the boss 7 and pass through 65 the open inner end of the same and the lon-

gitudinal conduits 8, and force the water in the tank out through the port 17. These tanks can of course be made of any required size, and it is only necessary to connect a sufficient number of them to a sunken 70 wreck to raise the same to the surface.

The longitudinal conduits 8 which are connected to the sides of the boss 7 enable the water and air when they enter the tank 1 to be more readily distributed, and the operation of filling the tank with water or pumping out the water by the force of the incoming air can therefore be more readily and easily effected.

It will be understood that, when the tank 80 1 is connected in position by means of the rings 3, it will normally remain in such position that the boss 7 will be below the same, and, if necessary, the diver may hold it in such relation when the pumping operations 85 begin. As soon as the air begins to be forced down through the conduit 18, the drain cock 6 first being closed, the water inside of the tanks begins to flow out through the water port 17, and the air of course rises 90 to the top of the tank. The water in the tank then acts as ballast to keep the same from revolving around on its side until all of the water in the tank has been discharged.

When the tank 1 has once been filled with 95 air it makes no difference what position it may assume, because of the manner in which the pipe terminating in the end 9 and leading to the water port 17 is bent. In other words, so long as the drain cock remains 100 closed and the air is not cut off from the conduit 18, no water can flow back into the tank. If the tank remains horizontal, with the boss 7 lowermost, of course the pressure 105 of the air inside of the same will be exerted upon the surface of the water in the boss 7, as long as the level of the water in this boss remains just about at the end of the pipe 9. Should it turn into vertical position, with either end uppermost, the air pressure will 110 be exerted down upon the surface of the water in the section 10 or the section 14, as the case may be, to check the inflow. Or should, for any reason, it be turned so that the water would be obliged to flow upward 115 through the section 16, to reenter the tank, the pressure of the air inside of the tank would be exerted on the surface of the water in this section or the transverse sections 11 and 13, and the inflow thus be effectively 120 stopped. Should the tank be in such position that the water would have to flow vertically down through the section 16 to enter the tank, air would be exerted on the surface of the water flowing upward through 125 the section 15, the slant of the section 15 being made sufficient for this purpose; and should the tank ever come to such a position that the drain cock 6 would point downward and the boss 7 upward, water would in this 130

case also be prevented from entering. This feature of my invention is very important, as sunken hulls do not always remain on an even keel when they are raised, but may roll 5 to some extent. It is of course unlikely that they will ever roll so as to move the tanks into all or any one of the extreme positions which I have mentioned. Consequently, the tank I have devised never becomes re-filled 10 with water when the water has once been pumped out of the same, so as to cause the vessel to sink to the bottom after the raising operations have been begun, under any conditions met with in actual practice.

15 From the manner in which the conduit 18 is bent on the inside of the tank 2, it will be seen that similar effects are secured. When the tank is being sunk down to be put in position by the diver, no matter in what 20 position he may take the same, that is, whether he takes it vertically with either end upward, or horizontally, with any part of the tank facing downward, there will always be a certain length of that portion of 25 the conduit 18 which is inside of the tank through which the water must pass in an upward direction to fill this conduit. In such a section it will be subjected to a downward action of the air pressure and stopped, 30 and it will be understood that this result will follow for any depth.

From the above description it will be seen 35 that I have devised an improvement in buoyancy tanks which is exceedingly simple in its construction and therefore can be readily and cheaply made, and which is also exceedingly efficient in use. When being taken down to be attached to a wreck by a diver, the water inside of the tank balances the 40 pressure of the water outside of the tank, and no crushing stress is exerted at any time upon the device. Furthermore, when the water in the tank is pumped out or forced out by the pressure of the incoming air, this 45 air pressure performs the same function as the water it is displacing, namely, it balances the external pressure on the outside of the tank and eliminates the crushing force of the water just as effectively.

50 My buoyancy tank can be used of course with submarine boats on account of the ease with which the same can be filled with water and emptied. Under any conditions of work I can either discharge the water entirely 55 therefrom or only in part. In this way I can regulate the buoyant effect of my invention so as to be able to keep a submarine boat in a condition of stable equilibrium at any depth when my tanks are used 60 for submarine navigation.

Having thus described my invention, I claim as new and desire to secure by Letters Patent:

65 1. A buoyancy tank comprising a hollow body, said body having a hollow boss pro-

jecting laterally therefrom, and a conduit leading through the wall of said body, said conduit being returned upon itself for a short distance inside of the body and then being bent to extend in a direction opposite to the return portion and toward said boss, 70 said conduit then being bent toward the point of entrance and then in the opposite direction toward said boss a second time, and then toward first one end of said tank 75 and then the other and then being bent down to enter the interior of the boss, and finally being bent so as to be returned upon said last-named bent portion and present its open inner end toward where the same enters the 80 body.

2. A buoyancy tank comprising a hollow body having a hollow boss extending laterally from one side, said body having an aperture therethrough, and a pipe leading 85 from said aperture, said pipe extending away from the interior surface of the tank and then extending toward said interior surface, and then extending first toward one end of the tank and then toward the other 90 end, and having a section which extends to the open inner end of the boss, said oppositely-extending sections and said last-named section being connected by transversely-extending sections, and the last-named section 95 having its inner end extending toward the bottom of said boss.

3. A buoyancy tank comprising a hollow body having a discharge opening, and having a hollow internal recess in the wall thereof, a pipe connected with said discharge opening and having a portion extending away from the wall of the body inside of the same and another portion extending at an acute angle to the first portion, said second-named portion terminating at the wall of the body adjacent the edge of the recess, the conduit then being bent first toward one end of the body and then toward the other and having its inner end located within said 100 recess.

4. A buoyancy tank comprising a hollow body having an internal recess in the wall thereof, and a conduit leading through the wall of said body, said conduit being returned upon itself for a short distance inside of the body, and then being bent to extend in a direction opposite the return portion and toward said recess, said conduit then being bent toward the point of entrance and then in the opposite direction toward said recess a second time, and then first toward one end of said tank and then the other, and then being bent to enter the recess, and finally being bent so as to 115 be returned upon said last-named bent portion and present its open inner end toward the point where the same enters the body.

5. A buoyancy tank comprising a hollow body, a conduit leading into the tank and 120

terminating adjacent the bottom thereof, said conduit having its upper portion formed into a compound coil extending transverse to the axis of the tank and consisting of oppositely-disposed connected S-shaped portions, and the lower portion of the conduit being formed into a coil extending approximately parallel with the axis of the tank, and means through which the 10 contents of the tank discharges when fluid pressure is supplied to the tank through said conduit.

6. A buoyancy tank comprising a hollow body having an internal recess in the bottom thereof adjacent the middle, a conduit 15 extending into the tank from the top and terminating in the said recess, said conduit having its upper portion formed into a com-

pound coil extending approximately transverse to the axis of the tank and consisting of oppositely-disposed connected S-shaped portions, and the lower portion of the conduit being formed into a coil extending approximately parallel with the axis of the tank, and means through which the contents of the tank discharges when fluid pressure is supplied to the tank through said conduit, said means extending to opposite sides of the said recess.

In testimony whereof I have signed my name to this specification in the presence of two subscribing witnesses.

ADOLPHE EHINGER.
